UNITED STATES PATENT OFFICE.

HERMANN HENRY HOFFMANN, OF CHICAGO, ILLINOIS.

LOOSE-LEAF-LEDGER BINDER.

SPECIFICATION forming part of Letters Patent No. 703,922, dated July 1, 1902.

Application filed May 21, 1901. Serial No. 61,325. (No model.)

To all whom it may concern:

- Be it known that I, HERMANN HENRY HOFFMANN, a citizen of the United States, residing at Chicago, in the county of Cook, State of Illinois, have invented certain new and useful Improvements in Loose-Leaf-Ledger Binders, of which the following is a description, reference being had to the accompanying drawings, and to the letters of reference marked thereon.
- 10 My invention relates to certain improvements in the class of loose-leaf-ledger binders shown in my Patent No. 568,251, dated September 22, 1896.
- The objects of the invention are to provide 15 an improved locking device capable of holding the leaves more firmly in the binder and at the same time allowing of an instantaneous opening and closing of the binder, to provide a stronger construction of the binder 20 proper, to provide a locking mechanism capable of applying the final clamping-pressure to the leaves after the binder has been given its initial clamping by hand-pressure. These objects I accomplish by the mechanism shown 25 in the accompanying drawings, in which—
- Figure 1 is a perspective of a loose-leaf ledger having my improved binder applied. Fig. 2 is a front perspective of the binder removed. Fig. 3 is a transverse longitudinal section thereof. Fig. 4 is a side elevation of the locking mechanism with parts broken away. Fig. 5 is an enlarged horizontal section on line 5—5, Fig. 4. Figs. 6 and 7 are detail views of parts of the locking mechanism, 35 and Fig. 8 shows one of the leaves.
- A and B designate the upper and lower covers, hinged at their rear edges to the adjacent edges of the upper and lower binder-sections C D in any suitable manner, said 40 binder-sections serving as the ledger-back, in which are clamped the loose leaves E.
- The binder-sections C D are formed of two L-shaped metal plates, having their vertical longitudinal flanges c d overlapped and with 45 the end edges d' of the section D bent around and inclosing the end edges c' of the sections C, so that a telescopic or sliding connection is established between the two sections.
- The ends of the binder are each closed by 50 two vertically-disposed L-shaped telescopic end posts or pieces c² d², also formed of metal, the post-sections c² being riveted at their up- per ends to the under sides of the ends of the horizontal flange c³ of the upper section C or to a strengthening-plate c⁴, riveted to said flange, and the lower ends of the post-sections d² being similarly affixed to the horizontal flange d³ of the lower binder-section or to a strengthening-plate d⁴ riveted thereto. The flanges c⁵ d⁵ at the forward edges of the posts 60 c² d² project inwardly, so that the end projections e on the leaves E may engage therewith, as shown in Fig. 1, and the flanges d⁵ are at their free edges bent around the corresponding edges of the flanges c⁵, so that the two 65 binder-sections will be firmly held together against accidental displacement, while being allowed a free movement one upon the other to clamp the leaves between them or release them. 70
- The two binder-sections C D are forced apart by the rods or plungers F F, secured to the section C and projecting into the tubes F' F', secured to the sections D and containing spiral springs f, which are compressed 75 when the binder-sections are forced together, and these springs quickly force the binder-sections apart at the instant the locking mechanism is released, as will now appear.
- G represents the telescopic lock-casing, 80 formed of the tubular upper member G', secured at its upper end to the upper binder-section C, and the lower tubular section G², secured at its lower end to the lower section D. These casing-sections are formed of sheet 85 metal and are U-shaped in cross-section, their rear open sides lying next to the back of the binder proper. The side walls of the upper casing members G' are slotted from their lower edges upward to straddle the guide-ribs g on 90 the outer sides of the lower casing member G², these ribs being, in fact, formed of the strips removed from the upper members in forming the said slots. Within the upper member of the lock-casing is swiveled the locking-screw 95 H, this being effected by mounting the upper unthreaded end of said screw in a bearing h, fixed in the casing, and this unthreaded end of the screw is provided with a keyhole or slot h', exposed through a round opening in the 100 middle of the horizontal flange of the upper binder-section C, as shown in Figs. 1 and 2. This screw H extends into the lower member G², where it is engaged by a pawl and releas-

ing mechanism I, which serves to lock the parts in their adjusted position in addition to serving as a nut in drawing the casing members together upon rotating the screw in the proper direction. The ends h^3 of the screw are beveled on their lower sides, so as to serve as ratchet-teeth when it is desired to press the upper binder-section C down upon the leaves, the teeth slipping past the nut-forming pawl I' and at the same time being engaged thereby on their upper sides to prevent any upward or return movement of the bolt, so that when the ledger-leaves are compressed initially in this manner the screw may then be rotated to the right to still further draw the binder-sections together upon them.

The pawl and releasing mechanism comprises a U-shaped nut-forming pawl I', pivoted at its upper ends in the upper end of the lower case member G² behind the screw H, so that its lower end may be swung into engagement therewith, the edge i' of the pawl being shaped concave to embrace the screw and properly beveled or inclined to engage the screw and serve both as a pawl and a nut, as follows: When the screw H is forced inwardly, the beveled sides of its threads h^3 will in descending force the pawl I' outwardly against the action of its spring I², to be presently described, and then the spring will snap the pawl back again over the upper abrupt sides of the threads. In other words, a pawl-and-ratchet action will be had. Then when parts are compressed as far as possible by hand the screw may be rotated to the right by its key, whereupon pawl I' will act as a nut, and so the screw will draw the two binder-sections together and apply the final pressure to the leaves.

In order that a quick release of the binder-sections may be had, I provide the lower end of the pawl I' with a releasing-dog I³, which is pivoted thereto, as shown at i^2 , to rock in a direction at right angles to the movement of the pawl, and provided next to the screw with a tooth i^3 to engage any one of a plurality of longitudinal grooves h^4 cut in the bolt and interrupting the threads thereof. The ends of the screw-threads at one side of these grooves are inclined, so that when the screw is turned to the right the tooth of the dog will ride up and pass them without acting on pawl I; but the ends of the threads h^3 at the opposite sides of these grooves h^4 are abrupt, so that when the screw is rotated to the left the said abrupt thread ends or groove-wall will engage the tooth of the dog I³ and rock the dog, so that it will press against its pivot i^2 and in turn press the pawl I' out of engagement with the screw. At this instant the springs f will expand and force the binder-sections suddenly apart. The dog I³ is further provided with a heel projection i^4 , which limits its movement in one direction by engaging the adjacent wall of the casing.

The spring I² is pivoted at its lower end on the cross-pin i^5 , passes upwardly under a re-

movable tension-pin i^6 , and at its free end bears on the rear straight edge of the dog I³, thus allowing a yielding movement to the dog, also serving as the spring for the nut-forming pawl I'. By removing the tension-pin i^6 the spring-and-pawl mechanism may be swung out or removed for repair, &c., their pivot-pins being also removable. 75

The operation, briefly restated, is as follows: The ledger-leaves E are placed in the binder and the top section C pressed down by hand as far as possible, the screw and its pawl operating as a ratchet and pawl and allowing of a quick closing movement. The final pressure to the sheets is applied by turning the screw to the right, at which time its pawl serves as a nut, and so the screw and pawl act at this time like a bolt and nut in drawing the binder-sections together. In thus turning the screw to the right the releasing-dog is not placed under any strain and exerts no influence on the pawl. When it is desired to open the binder and release the sheets for removal and replacement, it is simply necessary to give the screw a quarter-turn to the left, when the tooth of the dog I³ will snap into a groove h^4 , and then by a slight further movement of the screw in the same direction the dog will 90 lift the pawl out of engagement with the screw, whereupon the springs f will suddenly open the binder. It will be seen that the key need only be used in applying the final pressure to the binder and in giving the screw 100 the quarter-turn to the left. Moreover, only one keyhole is required instead of two, as in my former construction, and a single screw takes the place of the two racks and their 105 gearing.

Having thus described my invention, what I claim as new, and desire to secure by Letters Patent, is—

1. The combination, with binder-sections movable toward and from each other to clamp the sheets or leaves between them and release the same respectively, of a rotary ratchet-forming screw, mounted on one section, and a nut-forming pawl mounted on the other section in engagement with the screw-threads, whereby a quick closing may be had and thereafter a final screw-and-nut compression; substantially as described. 110

2. The combination, with binder-sections, movable toward and from each other to clamp the sheets or leaves between them and release the same respectively, of a rotary ratchet-forming screw mounted on one section, a nut-forming pawl on the other section in engagement with said screw, and means for releasing the pawl from the screw to allow of separation of the binder-sections; substantially as described. 115

3. The combination, with binder-sections movable toward and from each other, of a rotary ratchet-forming screw mounted on one section and grooved longitudinally, a nut-forming pawl mounted on the other section, and provided with a releasing-dog actuated 130

by one wall of the groove, upon a reverse turn of the screw, to disengage the pawl from said screw to allow of a quick opening of the binder; substantially as described.

5 4. The combination, with binder-sections movable toward and from each other, and springs to force the binder-sections apart, of a rotary ratchet-forming screw mounted on one binder-section and provided with longitudinal grooves, a nut-forming pawl mounted on the other binder-section in engagement with said screw, and a releasing-dog having a tooth to enter a groove in said screw, and by a reverse movement of the latter throw the 15 pawl out of engagement with said screw, whereupon the springs will suddenly force the binder-sections apart; substantially as described.

5 5. The combination with the binder-sections movable toward and from each other, telescopic rods and tubes mounted on the respective binder-sections, springs in said tubes pressing the said rods or plungers outwardly, of a telescopic tubular lock-case having its 25 members connected at their opposite ends to the respective binder-sections, a rotary ratchet-forming screw swiveled at its outer end in one case member, and provided with longitudinal grooves, a nut-forming pawl pivoted in the other casing member, and engaging said screw, a releasing-dog pivoted to the lower end of the pawl and having a tooth engaging the screw for operation by a reverse movement thereof, to release the pawl, and a 35 spring pressing the dog and the pawl toward the screw; substantially as described.

5 6. A binder comprising upper and lower sections formed of angle-plates overlapped at their back flanges to slide one upon the 40 other, the vertical end edges of the lower back flange being bent around and inclosing the corresponding edges of the upper back flange, telescopic angular end posts connected at their ends to the horizontal flanges of the 45 binder-sections to slide therewith, the vertical edges of the inwardly-projecting flanges of the lower post members being bent around the corresponding edges of the upper post members, and means for locking the binder-sections together; substantially as described.

5 7. A locking and releasing mechanism for binders comprising a telescopic case, a rotary ratchet-forming screw swiveled in one member of the case, a nut-forming pawl in the 55 other case member and engaging the screw, and means for disengaging the pawl from the screw upon reversing the rotation thereof; substantially as described.

5 8. A locking and releasing mechanism for 60 binders comprising a telescopic case, a rotary, longitudinally-grooved, ratchet-forming screw swiveled in one member of the case, a nut-forming pawl pivoted in the other case member, and engaging the said screw, a pawl-

releasing dog pivoted to the said pawl to engage 65 the screw-groove and by a reverse movement of the screw throw the pawl away from the screw; substantially as described.

9. A locking and releasing mechanism for binders comprising a telescopic case, a rotary, 70 longitudinally-grooved, ratchet-forming screw swiveled in one member of the case, a nut-forming pawl pivoted in the other case member, and engaging the said screw, a pawl-releasing dog pivoted to the said pawl to engage 75 the screw-groove and by a reverse movement of the screw throw the pawl away from the screw, and a plate-spring bearing at its free end on the rear edge of the dog and throwing it and the pawl toward the screw; 80 substantially as described.

10. A locking and releasing mechanism for binders, comprising a telescopic case formed of two tubular members formed respectively with longitudinally-extending guide-slots and 85 ribs, a rotary, ratchet-forming screw swiveled in one member of the case, a nut-forming pawl in the other case member, and engaging the screw, and means for disengaging the pawl from the screw upon reversing the 90 rotation thereof; substantially as described.

11. The combination with binder-sections, movable toward and from each other to clamp the sheets or leaves between them and release the same respectively, of a locking mechanism 95 including a ratchet device upon one section and a ratchet-engaging device on the other section, whereby a quick closing may be had, and means for imparting to the locking mechanism a final compression, and 100 means whereby when the locking mechanism is released, the parts are separated quickly; substantially as described.

12. The combination with binder-sections movable toward and from each other to clamp 105 the sheets or leaves between them and release the same respectively, of a locking mechanism including a rotary ratchet-forming screw mounted on one section, and means mounted on the other section for engaging the screw- 110 threads of the ratchet-forming screw, whereby a quick closing may be had and thereafter a final screw compression; substantially as described.

13. The combination with the L-shaped or 115 angular binder-sections, having overlapping sliding back pieces, one of which has its end edges bent around to inclose the end edges of the other section, whereby a telescopic or sliding connection is established between the 120 two sections, and a locking mechanism; substantially as described.

In testimony whereof I affix my signature in presence of two witnesses.

HERMANN HENRY HOFFMANN.
